(57) **CLAIM**

The ornamental design for a push switch, as shown and described.

DESCRIPTION

FIG. 1 is a front, top, and left side perspective view of a push switch showing my new design;

FIG. 2 is a rear, bottom, and right side perspective view thereof;

FIG. 3 is a front view thereof, the rear view being identical to the front view;

FIG. 4 is a left side view thereof, the right side view being identical to the left side view;

FIG. 5 is a top plan view thereof; and,

FIG. 6 is a bottom plan view thereof.

In the drawings, the broken lines depict portion of the push switch that form no part of the claimed design.

1 Claim, 6 Drawing Sheets
